EMBOSSED PAPER TOWEL

Robert Y. Kimura, Dobbs Ferry, N.Y., assignor to The
Procter & Gamble Company, Cincinnati, Ohio

Filed June 9, 1972, Ser. No. 261,579

Term of patent 14 years

Int. Cl. D5—06

U.S. Cl. D59—2 B

The single figure of the drawing is a plan view of an embossed paper towel showing my new design, the design unit being shown within the broken lines, the unit repeat being as indicated in the extensions beyond the broken lines. The background pattern extends over the entire design.

I claim:

The ornamental design for an embossed paper towel, as shown and described.
